UNITED STATES PATENT OFFICE.

IRA LUCIUS CLOUGH, OF WILLIAMSPORT, PENNSYLVANIA.

ROTARY ENGINE.

SPECIFICATION forming part of Letters Patent No. 299,350, dated May 27, 1884.

Application filed December 1, 1883. (No model.)

To all whom it may concern:

Be it known that I, IRA L. CLOUGH, of Williamsport, in the county of Lycoming and State of Pennsylvania, have invented a new and useful Improvement in Rotary Engines; and I do hereby declare that the following is a full and exact description of the same, reference being had to the accompanying drawings, and to the letters of reference marked thereon.

10 My invention relates to certain improvements in that class of rotary engines where in a single piston revolves within a stationary cylinder, and the supply of steam is cut off at a certain point in the revolution of the 15 piston, and the latter is caused to complete its revolution by expansion and centrifugal force of balance-wheel.

The object of these improvements is to enable the steam to maintain an almost even 20 pressure upon the piston during its revolution, and to cut it off at a point that shall not diminish this pressure or occasion more than one "dead" center or point.

The object, further, of these improvements 25 is to reduce frictional wear upon the valve, to increase the efficiency and durability of the engine, and at the same time reduce the number of its component parts and economize in the cost of their manufacture. The invention 30 therein consists in the construction and arrangement of parts, as hereinafter described with reference to the accompanying drawings, in which—

Figure 1 is a horizontal section of an engine constructed in accordance with my invention; Fig. 2, a transverse vertical section of the same; Fig. 3, a transverse central section of the cylinder and its contents; Fig. 4, a longitudinal vertical section in part of the 40 cylinder and its end inclosures; Fig. 5, a detail view of the packing-ring which is located between the heads of the spool and cylinder; Fig. 6, an end view of the spool-head; Fig. 7, a detail view of the cam and the rod upon 45 which it has direct action.

Like letters of reference denote corresponding parts in the several views.

A is the bottom or bed-plate which supports the entire machinery, and upon one end of 50 which is secured by any suitable means a saddle, B, and upon the opposite end an upright,

C, which serves as a support for the outer end of the valve-stem E'.

D represents the hollow stationary cylinder, which is mounted and secured upon the 55 saddle B by bolts or other suitable means. This cylinder has a side extension, D', parallel with the bed-plate A, and is provided with an interior chamber, a, and an end opening, a', the former inclosing the valve E, and the 60 latter serving to admit the stem E' of said valve. At the point where the valve-stem enters the cylinder-extension is a packing-box, b, screwed into a cap, b', which is secured to the cylinder-extension by means of set- 65 screws b''.

Longitudinally through the center of the cylinder proper passes a shaft, F, to which a spool, G, is keyed to revolve concurrently therewith. Between the heads of this spool fits the 70 valve E, which is provided with an end packing, constructed as hereinafter described with relation to the packing of the piston. This spool is constructed with a radial piston or wing, G', as illustrated in Figs. 2 and 3, said 75 piston being perforated at its outer end, and provided with a steam-packing, c, which is operated by the steam entering the small port c' and forcing out the packing, so that it is held in close contact with the cylinder-wall. 80 This packing works in a small chamber, d, of the port c', and is provided with shoulders d', which limit its forward-and-backward movement. The heads H H of this spool are of a diameter corresponding with that of the inside of the cylinder, and are beveled to adapt 85 themselves to fit snugly within the beveled flanges of the packing-rings H' H'. Within these packing-rings, around the shaft and against the heads of the spool, closely fit the 90 head-plates I I. To these head-plates and to the packing-rings H' H' are secured the heads J J of the cylinder by means of set-screws d d d.

K represents the steam-pipe, which branches 95 at any convenient point into the two arms K' K', which pass one through each head of the cylinder and into the head-plates at the ends of the spool, thus furnishing steam to the opposite ends of the spool simultaneously. The 100 branch pipes K' K' are screwed into an opening, e, in the head-plates I I, and this open-

ing registers at each revolution of the shaft and spool with steam-port e' in the heads of the spool. In the outer face of the heads of the spool are the steam-grooves e^2 , which extend from the steam-port e' about seven-twelfths of the distance (more or less, as found practical) around the heads of the spool, thus admitting steam into the cylinder during seven-twelfths of the revolution of the piston.

10 L is the exhaust-port, through which the steam exhausts after the piston has passed by it toward the valve E.

Upon one end of the shaft F is mounted a cam, M, which is keyed to and revolves with the shaft. This cam at every revolution acts upon the end of the cam-rod N, which is supported near this end between two rollers or other suitable devices, f f, of an upright, O. This cam-rod extends obliquely downward, 20 and pivotally connects at its lower end with the short rock-arm P, which is keyed to the rock-shaft Q, the ends of which have bearing in journal-boxes g g.

To the rock-shaft Q is keyed a long rack-arm, R, which extends vertically upward, and is pivotally connected at its upper end with the valve-stem e' at a point between its end support and the cylinder extension. At a point midway between the upper and lower connection of the rack-arm R is secured one end of a spiral spring, S, the other end of which is secured to the saddle which supports the cylinder.

From the foregoing description, and by reference to the accompanying drawings referred to as a part thereof, it will be manifest that the operation of this engine is as follows: The steam passes from the boiler into the steam-pipe K, and is conveyed through its arms K' 35 K' to the opposite ends of the cylinder, where it passes through the steam-ports and the head-plates and through the steam-ports and grooves in the heads of the spool, steam being supplied simultaneously at the ends of the spool, thus affording a perfect balance. The steam being admitted through these ports, as aforesaid, exerts force upon the radial wing or piston of the spool and causes it to revolve. The steam also enters the small port in the inner 40 end of the valve and forces inward the steam-packing, so as to prevent the escape of steam behind the piston. The steam also operates in a similar manner upon the steam-packing in the end of the piston, and thus confines the steam and prevents the loss of power. As the shaft F and the spool G revolve from the force of the steam, the cam m, which is keyed to the shaft, also revolves, and at each revolution forces out the cam-rod n. This movement of 45 the cam-rod forces downward the short rock-arm P, which, being keyed to the rock-shaft Q, causes said shaft to turn, which movement presses outwardly the long rock-arm R, it being attached to the valve-stem E', operates 50 upon said stem, and draws out the valve E just in time to permit of the passage of the

piston to complete its revolution. Immediately after the piston passes the valve resumes its normal position against the spool through the medium of the spring S, and the inlet 70 parts of the spool-heads again register with those in the head-plates.

By the construction, arrangement, and operation of the parts, as above set forth, it will be apparent that frictional wear is reduced to 75 a minimum, an almost even pressure is constantly maintained, and but one dead center or point occurs, and that between the exhaust and valve, where it has but little effect.

It will also be apparent that, instead of employing a spring as a means for restoring the valve to its normal position, other proper means could be substituted; and, further, the exhaust-pipe could be differently arranged in accordance with a change in the position of 85 the cylinder-inclosure.

Having thus described my invention, what I claim, and desire to secure by Letters Patent, is—

1. In a rotary engine, a revolving spool 90 mounted in the center of a stationary cylinder, and carrying a radial wing or piston, and two beveled heads provided each with a steam-port opening into the cylinder, and a groove extending from said port about seven-twelfths of the distance around the outer face of the head, substantially as and for the purpose set forth.

2. In a rotary engine, the combination of a revolving spool carrying a radial wing or piston and two beveled heads, a beveled ring fitting over each of said heads, and a head-plate fitting within each of said rings, and having steam-ports corresponding with those in the spool and cylinder heads, substantially as and 105 for the purpose set forth.

3. In a rotary engine, a stationary cylinder having a radial extension inclosing a horizontally-sliding valve operating in and out of the cylinder at regular intervals, and provided 110 with ports e' and chambers d , inclosing a packing, e , with shoulders d' , substantially as and for the purpose set forth.

4. In a rotary engine, a horizontally-sliding valve moved at regular intervals during 115 the revolution of the piston by a cam mounted on the piston-shaft, and operating a rod supported between friction-rollers and connecting with a rock-shaft carrying an arm connecting with the valve-stem, substantially as 120 and for the purpose set forth.

5. In a rotary engine, the combination of the cam M on shaft F, cam-rod N, rock-arm P, rock-shaft Q, connecting with the valve-stem E', and spring S, connecting with the cylinder-support, substantially as described and shown.

6. In a rotary engine, the combination, with the stationary cylinder and revolving spool mounted therein, of a steam-pipe branching 130 and entering the opposite ends of said cylinder, and terminating in head-plates located

next to the spool-heads and covering the grooved parts therein, substantially as and for the purpose set forth.

7. In the rotary engine described, the combination of the beveled packing-rings, head-plates, and cylinder-heads, held together and rendered adjustable by means of set-screws, substantially as described.

In testimony whereof I affix my signature in presence of two witnesses.

IRA LUCIUS CLOUGH.
